(57) **CLAIM**

The ornamental design for a vehicle bed cover, as shown and described.

DESCRIPTION

FIG. 1 is a rear elevational view of a vehicle bed cover showing our new design.

FIG. 2 is a top elevational view of the claimed design.

FIG. 3 is a right-side elevational view of the claimed design.

FIG. 4 is a front elevational view of the claimed design.

FIG. 5 is a bottom elevational view of the claimed design.

FIG. 6 is a left side elevational view of the claimed design.

FIG. 7 is a perspective view showing the vehicle bed cover of the claimed design in the closed position; and,

FIG. 8 is a perspective view showing the vehicle bed cover of the claimed design in the open position.

Portions of the figures shown in broken lines are for illustrative purposes only and form no part of the claimed design.
